SURGICAL INSTRUMENT

Raymond Arthur Mull, Benton Harbor, Mich.

Application March 3, 1942, Serial No. 433,111

1 Claim. (Cl. 128—1.4)

This invention relates to a surgical instrument, and more particularly to an electromagnetic surgical instrument for removing ferromagnetic metal fragments and particles from wounds and other parts of living bodies.

When metallic fragments become embedded in a living body, such as shell fragments or other fragments resulting from explosions or the like, it usually requires careful surgery to remove them. In order to gain access to the fragment it requires not only making an incision to reach the fragment, but frequently requires cutting away large portions of living tissue to enable forceps or other surgical instruments to get hold of the fragments so that the same may be withdrawn.

It has been found that an electromagnetic instrument of the type hereinafter described enables quick removal of ferromagnetic fragments by making a relatively small incision with a sterilized instrument. It has further been found in practice that the use of such an instrument frequently eliminates the need for a patient to be removed to the operating room of a hospital and permits removal of the fragment in the field or in a doctor's office.

As the term "ferromagnetic" shall hereinafter be employed, it refers to that small class of metals including iron, nickel and cobalt in which the magnetic permeability is vastly greater than for other substances.

It is an object of the present invention to provide an improved surgical instrument for extracting ferromagnetic objects or fragments from a living body.

It is a further object of the present invention to provide a novel electromagnetic surgical instrument in which all parts to be handled by the surgeon may be sterilized and which will remain free from contact with all other portions of the instrument not sterilized.

Another object of the present invention is to provide an electromagnetic instrument including an electric solenoid and a removable probe.

Another and further object of the present invention is to provide an electromagnetic surgical instrument including an electromagnet having a removable ferromagnetic core with a probe portion projecting from one end of the magnet and a handle projecting from the other end of the magnet, both the probe portion and the handle portion being of substantially less diameter than the internal diameter of the magnet.

The novel features which I believe to be characteristic of my invention are set forth with par-

ticularity in the appended claim. My invention itself, however, both as to its organization and manner of construction, together with further objects and advantages thereof, may best be understood by reference to the accompanying drawing, in which:

Figure 1 is a vertical sectional view of an electromagnetic surgical instrument with parts in elevation;

Figure 2 is a vertical sectional view with parts in elevation of the surgical instrument shown in Figure 1, with the core member about to be inserted in the electromagnet;

Figure 3 is a schematic view of the surgical instrument, connected through a foot switch to a battery; and

Figure 4 is a modified form of probe for the surgical instrument.

Referring now to the embodiment of the invention illustrated in Figures 1 to 3 of the drawing, there is shown therein a solenoid or an electromagnet 10 having a removable ferromagnetic core 11. The electromagnet 10 is provided with a large number of turns of wire and is arranged to be electrically connected to a battery 12 (Figure 3) through a cable 13 and a foot switch 14. The cable 13 includes two conductors 15 and 16 which are connected respectively to battery 12 and stationary contact 17 of foot switch 14. The foot switch 14 is provided with a second stationary contact 18 which is electrically connected through conductor 19 to the opposite side of battery 12 from conductor 15. Foot switch 14 includes a movable contact 20 which is carried on a button 21 and biased to a normally open position by a spring 22. When the button 21 is depressed by the foot or in any other manner, the movable contact 20 engages both of the stationary contacts 17 and 18, thereby energizing the electromagnet 10.

The electromagnet 10 is preferably covered by a rubber jacket 23 which enables frequent spongeing off of the electromagnet exterior with alcohol or other antiseptic solution.

The removable core 11 is formed of ferromagnetic material and preferably of material such as soft steel (i. e., a steel having a low carbon content). The core 11 includes a central portion 24 which is of such a diameter as to snugly but freely slip within the electromagnet 10, a handle portion 25 of reduced diameter and a probe portion 26, at the opposite end, of reduced diameter. In the form shown in Figures 1 to 3, the probe portion 26 has a blunt nose 27. This probe portion 26 is arranged to be inserted within a wound

or within an incision made in living tissue where the ferromagnetic fragment to be removed is lodged. The handle 25 is preferably knurled as is indicated in the drawing. The central portion 24 of the core 11 immediately adjacent the probe portion 26 is provided with a pin 28 which extends therethrough and which is arranged to engage the end 29 of the jacket 23 covering the electromagnet 10.

When the electromagnetic surgical instrument hereinbefore described is to be used to remove a ferromagnetic fragment, the member 11 is sterilized in the same manner as other surgical instruments are usually sterilized. The electromagnet 10 is washed off with alcohol or some other antiseptic solution. When the surgeon or doctor is ready to work on the patient, the surgeon is handed the core member 11 in a sterilized condition. An attendant holds the electromagnet 10 in the position as shown in Figure 2 of the drawing while the surgeon carefully drops the core member 11 through the central opening in the electromagnet 10. In doing so he is careful that the handle 25 does not touch the inner wall of the opening through the electromagnet 10. In this connection it will be noted that care is necessary only during the initial insertion of the handle portion 25 since the central portion 24 of the core member 11 as soon as it enters the opening in the electromagnet 10 will center the member 11 and prevent the handle portion 25 from thereafter touching the inner wall of the electromagnet. Movement of the member 11 through the central opening in the electromagnet 10 is stopped when the pin 28 strikes the end portion 29. The surgeon thereupon grasps the handle portion 25 and turns the instrument right side up as is shown in Figures 1 and 3. The pin 28 prevents the electromagnet 10 from sliding off the member 11.

Since neither the handle portion 25 nor the probe portion 26 has come into contact with any portion of the electromagnet 10, it will be observed that the probe portion 26 which enters the wound or incision, is still in a sterilized condition and furthermore the only portion of the instrument which is handled by the surgeon, namely the handle portion 25, also is still in a sterilized condition. The probe portion 26 is now inserted in the wound or incision to a position of approximate contact

with the fragment. The foot switch is thereupon closed by depressing the button 21 which causes the electromagnet 10 to be energized and the strong magnetic field produced thereby will engage any ferromagnetic fragments lodged therein and the same may be thereafter readily and quickly removed.

In Figure 4 of the drawing a modified form of probe portion is shown for member 11. More particularly, a tapered probe portion 30 is provided. Such a probe portion is more advantageous for certain type of wounds or incisions than is the blunt nosed probe portion 26 shown in Figures 1 to 3 of the drawing.

15 While I have shown particular embodiments of my invention, it will, of course, be understood that I do not wish to be limited thereto, since many modifications may be made, and I, therefore, contemplate by the appended claim to cover all such modifications as fall within the true spirit and scope of my invention.

I claim as my invention:

20 In combination, in a surgical instrument for removing ferro-magnetic fragments from living tissue, a probe element of ferro-magnetic material comprising a cylindrical body portion having an elongated reduced-diameter probe tip at one end and an elongated reduced-diameter handle at the other end, a small substantially cylindrical electro-magnet unit of a length no greater than said body portion and having a longitudinal cylindrical opening of a diameter to receive said body portion slidably, and stop means on said probe element extending laterally therefrom between said body portion and said probe tip engageable with the adjacent end of the electro-magnet unit for supporting the latter while the assembly is carried by said handle, the reduced diameter handle permitting the probe element in 25 sterilized condition to be assembled with the electromagnet unit by dropping it handle first into the opening therefor while maintaining the handle uncontaminated and entirely out of contact with the electro-magnet unit, said handle including anti-slip means thereon for assuring positive handling of the assembly without any need for touching the solenoid during an operation.

RAYMOND ARTHUR MULL.
